METHOD OF MAKING CLOSURE CAPS

Louis A. Von Till, Freeport, N. Y., assignor to
Anchor Cap & Closure Corporation, Long Island
City, N. Y., a corporation of New York

Application March 12, 1941, Serial No. 382,908

3 Claims. (Cl. 113—121)

The present invention relates more particularly to a method of making closure caps.

Great difficulty has been encountered in the closure and glass container art in the manufacture of threaded closures and threaded containers which will mate properly. The difficulty arises because neither closures nor glass containers can be made accurately to specifications. In addition, there has been a definite limitation in the distance that closure threads can be rolled inwardly without rupturing the metal. Glass manufacturers follow specifications set up by the Glass Container Association which allow tolerances of about forty-thousandths of an inch in the diameter of glass finishes of the seventy millimeter size. This is the size of finish used for fruit jars and large size jars of mayonnaise. Cap manufacturers are required to keep within a tolerance of ten-thousandths of an inch variation in the diameter of the cap for the above size glass finish. The maximum commercial depth of screw threads on closure caps under practices heretofore has been forty-thousandths of an inch. The thread projection on the glass container is about sixty-thousandths of an inch.

A closure of minimum size may be applied to a jar of maximum size. In such instances the closures must go on and must not fit too tight. If it fails to function properly, the packer will complain. Likewise a maximum cap may be applied to a minimum size jar. In such a case it must not fit too loose and it must form a good seal to prevent complaints. In many cases the allowed tolerances are exceeded because it is not practical to place a gauge on either the individual closures manufactured or on the individual glass containers. They can only be checked at intervals with the assumption that all of the unchecked closures and containers are in accord with those checked. Thus a closure or container may have variations which exceed the allotted tolerances. It is therefore important that closures can be adapted to accommodate maximum and minimum sizes of glass containers, and, if possible, variations slightly above and below the prescribed tolerances. Usually when the cap does not fit properly on the container, the thread of the closure tends to ride over the thread on the container which causes the cap to cock or to bulge at one point. In either event an imperfect seal is formed and the closure is hard to remove. Another difficulty is that the thread on the container may vary slightly in its vertical position or it may be wavy. The closure has to

accommodate such irregularities without materially impairing the sealing operation.

The present invention aims to overcome or minimize the above difficulties by providing a method of manufacturing closures in which the thread means may be rolled deeper without rupturing the metal of the cap and by providing a closure with thread projections having extraordinary depth which will bend independently in a vertical direction without substantial distortion of the skirt in a circumferential direction, and otherwise to provide a more perfect fit between the closure and the container. The invention aims to accomplish the above results without increasing the amount of metal required for the closure and without increasing the cost of manufacture thereof.

An object of the present invention is to provide an improved method of making closure caps by which a deeper and more effective thread means may be provided.

Another object of the invention is to provide an improved method of manufacturing closure caps wherein the metal which accumulates in front of the thread roller is formed into a reinforcing arch.

Another object of the invention is to provide an improved method of rolling knurls in a threaded cap which will not interfere with the application of the cap to a container.

Another object of the invention is the provision of a method of making a closure cap having screw projections arranged substantially end to end which will yield independently in a vertical direction.

Another object of the invention is the provision of a method of making a closure cap having spirally arranged screw projections, the ends of which are sufficiently near abutting relation to prevent substantial circumferential deformation in the skirt of the cap.

Another object of the invention is to provide a method of making a closure cap having sectional screw projections yieldable independently in a vertical direction with the sections sufficiently close to each other to prevent substantial circumferential deformation of the skirt.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein

Fig. 1 illustrates the first step in the preferred method of manufacture;

Fig. 2 illustrates the second step in the preferred method of manufacture;

Fig. 3 illustrates the third step in the preferred method of manufacture;

Fig. 4 is an enlarged fragmentary sectional view illustrating a minimum size closure applied to a maximum size container;

Fig. 5 is an enlarged fragmentary sectional view illustrating a maximum size closure applied to a minimum size container finish;

Fig. 6 is an enlarged fragmentary sectional view taken intermediate the ends of two thread projections along the line 6-6 of Fig. 7;

Fig. 7 is a fragmentary elevational view of a portion of the inside of the skirt of the cap illustrating the thread projection;

Fig. 8 is a fragmentary sectional view lengthwise of the thread along the line 8-8 of Fig. 7;

Fig. 9 is a sectional view of a closure applied to a container having a wavy thread, the irregularities being shown in exaggerated form; and

Fig. 10 is an enlarged fragmentary view illustrating in exaggerated form the behavior of the metal of the closure in rolling the thread projection.

Referring again to the drawings, there is shown in Fig. 1 a hat-shaped blank having a cover portion 1, a depending skirt 2 and a lateral flange 4. Such blanks are stamped in the usual manner from lacquered or coated tinplate and may have a sealing bead 5 for pressing the liner against the rim of the container, formed in the cover portion thereof at the same time. Such blanks are then delivered to a rolling machine under the present method which rolls the flange 4 into a bead or wire edge 6. At the same time the rolling tools form a groove 7 in the skirt of the cap adjacent the cover part thereof. These grooves may be formed either by rolling the metal of the groove outwardly or by rolling the metal of the skirt below the groove inwardly. Preferably it is formed by rolling the metal in the groove outwardly as this simplifies the manufacture of the closure.

Thereafter threading tools engage the blank and roll a series of thread projections 10 in the skirt of the cap separated by intermediate portions 11 which are preferably substantially arch shaped for the purposes described hereinafter. Preferably at the same time that the thread is being rolled the groove 7 has formed therein corrugations 12. These corrugations facilitate gripping the closure in the application and removal thereof and in addition improves the appearance thereof.

In the rolling of continuous spiral threads in a closure the metal piles up in front of the threading tool somewhat similarly to the piling up of dough in front of a rolling pin. In the manufacture of closures this piling up of metal is sufficiently great in some instances to cause the buckling of the metal under the roller. Also in rolling a continuous thread the metal has to be drawn from the two sides of the thread. It is entirely a stretching operation. Additional metal has to come from somewhere in pressing the thread groove in the skirt of the cap and the only place available is from the sides of the

thread. In some instances manufacturers have tried to minimize the strain on the metal by permitting the skirt of the cap to collapse or shorten during the rolling operation thereby endeavoring to obtain an accordion effect. Such collapsing increases the amount of metal required in a closure of a given height and in addition prevents accurate control of both the shape and the depth of the thread. In addition the length of the skirt of the cap is decreased noticeably where the thread overlaps, there being two plaited where in the remainder of the skirt of the cap there is but one. The more common practice at the present time is to clamp the metal on the two sides of the thread to prevent a decrease in the height of the skirt and to draw the metal from the two sides of the thread. I have discovered that much deeper thread projections may be formed by permitting the metal which piles up in front of the roller to form relatively short interruptions in the thread. In this way strain on the metal at the sides of the thread is relieved at short intervals and in addition the metal for the thread projections may be drawn from four directions where previously it has been drawn from two directions. In this way it has been found that the depth of the thread projections can be increased in commercial practice from the former depth of forty-thousandths of an inch to sixty-thousandths of an inch.

The mechanism for forming the thread may be varied, but a preferred form is shown in Fig. 10 wherein a large disc 14 has a thread rib 15 formed thereon with interruptions or indentations 16 at short intervals therein. Cooperating with the disc 14 is a chuck or a roller 17 of smaller size than the diameter of the cap which fits into the cap blank as illustrated in Fig. 10. The metal as it begins to pile up in front of the roller 18 as shown at 18 is permitted to bulge into the recesses 16 of the thread rib 15 thereby preventing excessive accumulation of metal in front of the roller and also minimizing the tendency of the metal to buckle in front of the roller at that point. In addition, as it will be noted in Fig. 10, the metal being forced inwardly into the projections may be drawn from four sides. The strains on the metal at the sides of the thread are relieved at the interruptions 11. By utilizing this method the depth of the thread may be increased substantially fifty percent without subjecting the metal to more than the customary amount of strain. In fact it has been found that fewer instances of rupture are encountered in the manufacture of the present closures with the increased depth of the thread than in the previous manufacture of continuous thread closures with a much less depth of thread.

The best results have been obtained with the present method and the best operation with the resulting closure by making the thread projections 10 about $\frac{1}{4}$ to $\frac{3}{8}$ of an inch in length with the intermediate interruptions 11 about $\frac{1}{8}$ of an inch in length. It is to be understood that these dimensions may be varied within limits, but excellent results have been obtained with the above specifications.

The closure is shown applied to a container 20 in Figs. 4, 5 and 9, having a spiral thread 21 thereon. In Fig. 4 a minimum size cap is shown on a maximum size container. It will be noted in this figure that the distance between the inner side of the thread projections 10 and the outer wall of the container is substantially the same as the distance between the outer edge of the con-

tainer thread 21 and the inner side of the skirt of the cap. By utilizing applicant's method it is possible to increase the depth of the thread from about forty-thousandths of an inch to sixty-thousandths, thereby making the thread projection in the closure project inwardly as far as the thread on the container projects outwardly. Since Fig. 4 illustrates a minimum size cap of a maximum size container, the clearance between the thread of the container and the skirt of the cap as well as the clearance between the thread of the cap and the wall of the container is small.

In Fig. 5 the other extreme condition is shown in which a maximum size cap is placed on a minimum size container. In such a case the gap between the outer edge of the container projection 21 and the skirt of the cap and likewise the gap between the inner side of the cap thread 10 and the outer wall of the container is about forty-thousandths of an inch. The actual engagement with the thread is approximately twenty-thousandths of an inch whereas in Fig. 4 the engagement is more nearly sixty-thousandths of an inch.

In addition to the size variations shown in Fig. 4, closures are required to accommodate threads on the container which vary in height. In many cases the threads are wavy as shown more particularly in Fig. 9 where the thread has a downward wave as shown at 24 and an upward wave as shown at 22. The series of spirally arranged end to end projections 10 tend to act independently in a vertical direction. Hence when a wavy portion 22 is engaged, the individual projections will be bent downwardly to take care of the irregularity. With a continuous type thread there would not be the same vertical flexibility. In addition the thread would be bent down for a substantial distance on each side of the downward projection. With the present closure a continuous holding contact is formed on the downward projection 22 and also at the sides thereof. The projections form in effect a chain or a series of spring tongues which adjust themselves to the irregularity of the thread and follow it around its underside.

One of the most troublesome problems encountered in sealing glass containers is the tendency for a closure to cock or buckle up on one side. The tendency of the closure thread to ride over the container thread forces the skirt outwardly which acts as a lever to bend the closure cover at that point upwardly. Such instances are very noticeable particularly with smaller closures and are quite objectionable because they impair the seal and cause spirited complaints by packers. In the present closure the interruptions between the projections 10 are sufficiently short so that they form substantially arch-shaped portions 11 and hence reinforce the closure in a circumferential direction and tend to prevent the projections 10 from moving outwardly. The arch construction is a very strong one and it has been found very effective in preventing distortion of the skirt in a circumferential direction and the resulting cocking and bulging of the cover part of the cap about the sealing surface. The construction of the portions of the skirt intermediate the thread projections 10 is shown at 11 in the fragmentary sectional view of Fig. 6 and also at 11 in the enlarged elevational view in Fig. 7 and the horizontal sectional view in Fig. 8.

Another feature of the closure is the elimination of interference between the thread projection 21 and the knurls of the closure, the knurls being set outwardly with respect to the skirt of

the cap. The upper end of the thread projection does not engage the knurls of the closure even when a minimum size cap is applied to a maximum size container as shown in Fig. 4.

5 The present closures are applied in the same manner as other types of screw closures. They may be hoppered into the usual sealing machines and applied at a rapid rate with severe sealing forces. The individual projections 10 conform substantially to the thread on the container even when there are substantial irregularities therein and an effective seal will be provided and a minimum effort will be required in removing the closure.

15 It will be seen that the present invention provides an improved method of manufacturing closure caps in which screw threads of unusual depth may be formed. The method does not increase the amount of metal required in the closure or increase the cost of manufacture. In addition the resulting closure has an improved thread and will take up a much greater variation in size of container than closures manufactured heretofore. The independent spirally arranged 20 end to end projections permit a greater depth of thread projection and in addition cooperate to conform to the underside of the thread of the container, thereby to make a more effective seal. The arch portions intermediate the thread projections reinforce the closure and minimize circumferential distortion and the resulting tendency of the closure to cock. The method may be applied with minimum changes in existing machinery and hence can be introduced commercially at a minimum cost.

25 As various changes may be made in the form, construction and arrangement of the parts herein without departing from the spirit and scope of the invention and without sacrificing any of 30 its advantages, it is to be understood that all matter herein is to be interpreted as illustrative and not in a limiting sense.

35 Having thus described my invention, I claim:

1. The method of making closure caps with a 40 screw thread in a cylindrical skirt, which method comprises rolling inwardly, substantially to the limit of the stretching that the metal will withstand without rupture, a spirally arranged projection in the cylindrical skirt of the closure cap to form a part of the closure thread, rolling a 45 succeeding like projection of said thread at a selected distance from the end of the first projection to leave the excess metal in front of the roller in the intermediate portion, thereby to reduce the strain on the metal in the projection and also to a greater extent the strain on the 50 metal of the intermediate portion, and, in rolling said like projection, drawing part of the material from the less strained intermediate portion into said succeeding like projection and repeating 55 said step to form the complete thread.

2. The method of making screw closure caps with screw projections in a cylindrical skirt which 60 method comprises rolling radially inwardly an 65 extraordinarily deep spiral groove on the exterior of the cylindrical skirt to form a screw thread portion on the interior of the skirt of the closure, and reducing the strain on the metal occasioned by metal piling up in front of the 70 roller forming the groove by forming interruptions in the groove which take up the excess metal that piles up in front of the roller and pulling part of the metal for rolling each succeeding portion of the groove from the metal of the preceding interruption, the metal at said

interruptions being subjected to substantially less strain than the metal of the portions of the groove intermediate the interruptions.

3. The method of making a screw closure cap which comprises mounting a cap blank on a roller having an uninterrupted spiral thread forming groove therein, rolling said cap blank along a mating threading section having spaced indentations therein to form a spiral screw thread in the cap and forming ribs across said thread in

part from the excess metal, which piles up in front of the roller being bulged successively into said spaced indentations on said mating threading section during the rolling of a thread to thereby take up the excess metal occasioned in rolling the part of the thread immediately preceding the rib and to supply part of the metal for forming the part of the thread immediately succeeding the rib.

10

LOUIS A. VON TILL.
